UNITED STATES PATENT OFFICE.

BENJAMIN DENVER COPPAGE, OF WILMINGTON, DELAWARE.

COMBINED SCRAPING AND CONVEYING MEANS FOR CENTRIFUGAL MACHINES.

1,030,974.

Specification of Letters Patent. Patented July 2, 1912.

Application filed September 16, 1911. Serial No. 649,605.

To all whom it may concern:

Be it known that I, BENJAMIN DENVER COPPAGE, of Wilmington, Delaware, have invented a new and useful Improvement in 5 Combined Scraping and Conveying Means for Centrifugal Machines, which invention is fully set forth in the following specification.

This invention has been designed with 10 particular reference to centrifugal machines of the type illustrated in U. S. Letters-Patent to C. S. Lee, No. 882,256, dated March 17th, 1908, wherein a perforated or foraminated cylinder, screen or drum, designated 15 the "rotor," is rotated at high speed—approximately one thousand revolutions per minute—on an approximately horizontal axis, and has within it relatively fixed or non-rotatable means acting in conjunction 20 with the rotation of the rotor for conveying the material through the latter at the desired speed of travel. A fixed spiral conveyor blade with a slight clearance between its peripheral edge and the inner surface of 25 the rotor works very satisfactorily with materials such as sand, for the thin covering of sand which the clearance permits to be formed on the interior surface of the rotor allows water to drain therethrough and to 30 be discharged through the perforations of the rotor by the centrifugal action. Such thin covering of sand also affords a frictional contact with and grip upon the main body of the material in the rotor, causing 35 the same to be whirled about with the rotor, and is in this respect advantageous. But in acting upon materials, such for example as coal, for drying the same preparatory to 40 coking, which coal contains small portions of clay, or coal dust, or both, there is a tendency to form about the interior surface of the rotor a tightly compacted covering impervious to water, and which therefore interferes with the expulsion of water there- 45 through and through the perforations of the rotor by centrifugal force. Therefore, the object of my present invention is to provide, especially for use with materials which tend to form such an impervious coating or cov-

ering, means for both scraping such covering from the surface of the rotor and for conveying the material being treated through the rotor at the desired speed of travel. Such means constituting the invention may be best understood and described 55 by reference to the accompanying drawings illustrating embodiments thereof, and wherein—

Figure 1 is a longitudinal section through parts of a centrifugal machine of the type 60 referred to equipped with improved conveying and scraping means of this invention; Fig. 2 is a transverse section on line 2—2 of Fig. 1; Figs. 3 and 4 are detail views of parts shown in Figs. 1 and 2; Fig. 5 is a longitudinal sectional view through a rotor equipped with another form of combined conveyer and scraper means in accordance with my invention; Fig. 6 is a transverse sectional view of Fig. 5; and Figs. 7 and 8 are detail views of 70 parts shown in Figs. 5 and 6.

Referring first to Figs. 1 to 4, inclusive, 10 is a perforated or foraminated screen, cylinder or drum adapted to rotate, in bearings about its middle, on an approximately 75 horizontal axis. In the particular construction of machine illustrated, these bearings consist of three pairs of wheels spaced equidistant about the rotor, only one pair being shown in Fig. 1. 11 is a fixed core extending longitudinally through the rotor and supported at its ends respectively by a hopper 12 and discharge hood 13, which parts are fixed to the machine casing. 14 is the spiral blade of a single flight ribbon conveyor supported at intervals from the core 11 by radiating arms 15. There is a slight clearance between the peripheral edge of blade 14 and the inner surface of rotor 10, sufficient to allow for a 90 thin covering about the interior surface of the rotor of the material being acted upon. 16 is an arm fixed to core 11 by means of caps 17, 17, and bolts 18. 19 is a U-shaped frame having a scraper blade 20 fixed thereto; this frame embraces between its arms the outer end of arm 16 and a bolt 21 pivots the frame on said arm 16. The end of the

two arms of U-shaped frame 19 are bent to form pockets which are loaded with lead 22, to give counterbalancing weight at that end of the frame sufficient to tilt the blade 20 upward with its edge yieldingly in contact with the inner surface of rotor 10. With the rotor turning against the edge of the scraper blade (as shown in Fig. 2), the latter scrapes from that portion of the interior surface of the rotor which it contacts any material carried by said surface, such loosened material dropping down to the bottom of the rotor and being thereby whirled, along with the main body of the material, against the conveyer blade 14, and thus advanced toward the discharge end of the rotor. As shown in Fig. 1, there are two of these scrapers, one in each end of the rotor. Their blades do not scrape the entire inner surface of the perforated wall of the rotor, leaving portions thereof unscraped to afford a frictional contact with and grip upon the main body of the material to be whirled about with the rotor.

Figs. 5 to 8, inclusive, illustrate another form of construction employing pivotal scrapers. 25 is a perforated rotor with a core 26 extending longitudinally therein. Hubs 27 keyed on the core are spaced equidistant and held in this position by set screws 28. Each hub has a depending arm 29 and an arm 30 extending upward in an oblique position. Arm 29 has at its lower end a deflecting plate 31 set on a bias or obliquely with relation to the axis of the rotor and having a curved lower edge slightly clearing but conforming to the curvature of the inner surface of the rotor. Rotation of the rotor 25 (in the direction of the arrow Fig. 6) carries the material being acted upon against the face 32 of the plate 31, thus advancing said material within the rotor toward the discharge end of the latter. Each plate 31 thus constitutes in effect a section of a conveyer. At the outer end of each arm 30, there are two oppositely projecting pivot studs 35 and 36. The stud 36 on one arm and the stud 35 on the next arm engage sockets of a pivotal scraper 37, there being a succession of these scrapers thus positioned between the arms. Each scraper has a tail piece 38 which is weighted to counterbalance the scraper part, which is on the other side of the axis of the pivots, thus holding the scraping edge yieldingly in engagement with the interior surface of the rotor. The tail-piece has an ear 39 and a deflecting surface 40 oblique to the axis of the rotor. With the rotor turning in the direction of the arrow, Fig. 6, each scraper 37 removes from a portion of the interior surface of the rotor any material carried thereby, and such dislodged material drops or is thrown against the inclined surface 40,

and thereby deflected and advanced toward the discharge end of the rotor. With the scrapers 37 and their deflecting surfaces 40 thus positioned in effect between adjacent deflecting plates 31, means are provided for advancing or conveying all material in the rotor toward the discharge end of the latter. Between adjacent scrapers there are bands of the interior surface of the rotor not contacted by the scraping edges. These unscraped portions of the surface afford frictional contact with and grip upon the main body of the material sufficient to cause the same to be whirled about with the rotor.

What I claim is:

1. In a machine of the character described, the combination with a rotor, of one or more scrapers within the rotor, and means holding said scrapers in yielding engagement with the interior surface of the rotor.

2. In a machine of the character described, the combination with a perforated rotor adapted to receive at one end and to deliver from its other end, one or more scrapers within the rotor and yieldingly engaging the interior surface thereof, and conveyer means for advancing material through the rotor from its intake end to its discharge end.

3. In a machine of the character described, the combination with a perforated rotor, of one or more scrapers pivotally supported within the rotor, and means turning said scrapers on their pivots to apply their edges into yielding contact with the inner surface of the rotor.

4. In a machine of the character described, the combination with a perforated rotor, of one or more scrapers pivotally supported within the rotor, and counterbalancing weight holding each scraper with its edge in yielding contact with the inner surface of the rotor.

5. In a machine of the character described, the combination with a perforated rotor, of a succession of scrapers pivotally supported within the rotor, each scraper having a deflecting surface for advancing material toward the discharge end of the rotor, and means holding said scrapers in yielding engagement with the interior surface of the rotor.

6. In a machine of the character described, the combination with a perforated rotor, of a core extending longitudinally therein, arms radiating from said core, and scrapers pivotally supported on said arms with their edges in yielding contact with the inner surface of the rotor.

7. In a machine of the character described, the combination with a perforated rotor, of a core extending longitudinally therein, arms radiating from said core,

scrapers pivotally supported on said arms with their edges in yielding contact with the inner surface of the rotor, other arms radiating from said core, and conveyer means supported by said other arms and adapted to advance material toward the discharge end of the rotor.

In testimony whereof I have signed this specification in the presence of two subscribing witnesses.

BENJAMIN DENVER COPPAGE.
